UNITED STATES PATENT OFFICE.

DAVID ALEXANDROVITCH RUFFMAN, OF HYDE PARK, LONDON, ENGLAND.

BIDET.

1,348,518.

Specification of Letters Patent. Patented Aug. 3, 1920.

Application filed January 18, 1919. Serial No. 271,836.

To all whom it may concern:

Be it known that I, DAVID ALEXANDROVITCH RUFFMAN, a citizen of Russia, whose post-office address is 21 Queensborough Terrace, Hyde Park, London, England, have invented new and useful Improvements in or Connected with Bidets, of which the following is a specification.

My invention relates to the arrangement 10 of a bidet pan in combination with the pan of a water-closet.

According to my invention a bidet pan is hinged or pivoted or adapted to slide or mounted on links or otherwise in such a 15 manner with relation to the W. C. pan that when required for use it can be moved over, into or adjacent to the W. C. pan, and means are provided whereby the contents of the bidet pan can be discharged into the 20 W. C. pan or into a separate trap, sink or pipe provided for the reception of the waste. I provide a water supply in connection with the bidet pan, preferably both hot and cold.

25 A convenient arrangement for carrying my invention into practice is illustrated in the accompanying drawing, in which:—

Figure 1 is a sectional side view showing a bidet arranged in conjunction with an 30 ordinary W. C. pan, and

Fig. 2 is a sectional front elevation.

Fig. 3 is a view of part of Fig. 1 drawn to a larger scale.

Fig. 4 is a plan view of the bidet detached.

35 Fig. 5 is a view similar to Fig. 3 illustrating a slight modification of the arrangement shown in the said figure.

a indicates the ordinary W. C. pan which, as shown, is connected to a soil pipe *b* and 40 as having connected to it a flushing pipe *c*, and *d* indicates the ordinary hinged seat.

e indicates the bidet which is advantageously made of sheet metal and preferably metal of a light nature such as aluminium, 45 the said bidet being provided with a well or basin *f* which fits within the ordinary flushing rim of the pan *a*, and with a hollow rim *g* designed to rest upon the top of the pan and form the seat of the bidet, the inner 50 edge of the said rim preferably slightly overhanging the edge of the basin, in a manner which will be clearly understood by reference to Figs. 1 and 2.

To the rim *g* of the bidet is attached a 55 pipe *h*, preferably in connection with hot and cold water supplies as at *i*, *i*. In order

to allow of the bidet being lifted from the pan *a* to such a position that it will permit of the ordinary seat *d* being turned down on to the said pan, the said pipe *h* is, in 60 the drawing represented as being made in sections or links connected by joints *k*, *k* which will permit of the said pipe being folded, and of the bidet being lifted to a position such, for instance, as indicated by 65 the dot and dash lines in Figs. 1 and 2.

The joints *k*, *k*, as shown, are of a type which will only allow of the said pipe being folded so that the sections lie parallel to one another, this arrangement permits of the 70 bidet, when lifted, being supported by the pipe and say by a hook *l*. When, however, it is more convenient to arrange for the bidet, when not in use, to occupy a position say to one side of the W. C. pan instead 75 of vertically above it, as shown, the joints *k*, *k* may be of the universal type.

Between the rim *g* and the basin *f* I provide an opening *m*, Figs. 2 and 4 through which the water which is introduced into the rim will flow into the basin, and at the rear of the basin I provide a nozzle *n* normally closed by a plug *o* for the discharge of the water from the basin. This plug is connected to a rod *p* which extends to the top-side of the rim where it is provided with a head *q* for lifting the said rod. As shown, the upper end of the rod *p* is screw-threaded and is fitted into a nut *r* so that the lifting of the plug *o* will 90 be effected by rotating the head *q*.

In practice I prefer that the water which enters the rim should, before entering the basin, flow completely around the said rim so that, when warm water is used, the said 95 rim may be warmed, and I therefore provide between the inlet of the pipe *h* and the outlet *m* a partition *s* as shown in Figs. 2 and 4. When cold water only is required it is 100 advantageous that such water should directly enter the basin *f* without flowing around the rim and to provide for this I prefer to make the rod *p* tubular and provide apertures in it at *t*, *u*, the upper aperture *t* being normally closed by a plug *v* having its head *w* resting upon the head *q*.

It will thus be understood that when the plug *v* is lifted the water which enters the rim will flow through the opening *t*, the hollow rod *p* and the opening *u* directly into the 110 basin.

To prevent the water from running

around the rim I may arrange adjacent to the water inlet a baffle α over which the water will only flow when the opening t is closed by the plug v .

- 5 In some cases, instead of providing the rod p for lifting the waste plug o , the said plug may be provided with a chain y , as shown in Fig. 5, and in this case an independent plug y^1 on, say, a screwed rod is 10 provided for admitting the water directly into the pan f from the rim g without the necessity for traversing around the latter.

z indicates a spoon shaped lip which I advantageously provide in connection with the 15 waste nozzle n for preventing water from dripping from the said nozzle when the bidet is in its raised position, as indicated by the dotted lines in Fig. 1.

It is to be understood that the construction hereinbefore described is only given 20 as an illustration of a way in which my invention can be carried into practice and that the bidet can be mounted in any other convenient manner which will allow of it being 25 readily placed upon or removed from the pan of a W. C. It is also to be understood that, although I prefer that the pan should be arranged in conjunction with a W. C. pan having a hinged seat, it may be used 30 in connection with a W. C. pan having a fixed seat in which case the bidet itself will, when in use, rest upon the seat.

Claims:

1. A bidet designed for use in connection 35 with a water closet comprising a basin and a hollow rim which latter forms the seat of the bidet and into which hollow rim the water is introduced, the basin of the said bidet being provided with a discharge nozzle 40 through which the contents of the bidet can be discharged into the water closet pan.

2. A bidet designed for use in connection 45 with a water closet comprising a basin and a hollow rim which latter forms the seat of the bidet and into which hollow rim the water is introduced, the basin of the said

bidet being provided with a discharge nozzle through which the contents of the bidet can be discharged into the water closet pan in combination with means whereby the water 50 before being introduced into the basin of the bidet is caused to traverse around the hollow rim of the latter.

3. In a bidet of the kind claimed in claim 1, the combination with the hollow rim of 55 the bidet of a plug connected to a hollow screw threaded tubular rod, a head for lifting said rod, apertures in said rod, the upper aperture being normally closed by a second plug having its head resting upon the head 60 of the hollow tubular rod.

4. The combination with a water closet bowl, of a tubular rim forming a seat adapted to rest on the upper edge of the closet bowl, a pan supported by said rim, means 65 placing the pan in communication with the interior of said rim, and means for supplying fluid to the interior of said rim.

5. A combination as defined in claim 4 having means for closing the communicating 70 means between the interior of the rim and pan.

6. A combination as defined in claim 4 in which the means for supplying fluid to the interior of the rim includes a hot water 75 pipe and a cold water pipe, valves arranged in each of said pipes for controlling the flow of water through the same, and a common pipe placing both of said pipes in communication with the interior of the rim. 80

7. The combination with a water closet bowl, of a hollow rim forming a seat adapted to rest on the upper edge of the bowl, a basin carried by the rim and extending into the bowl, means placing the interior of the 85 rim in communication with said basin, a valve for closing the last named means, a water supply pipe, a hinge jointed pipe connecting the last named pipe with the interior of the rim, and an outlet for the basin. 90

DAVID ALEXANDROVITCH RUFFMAN.
